DESIGN FOR AN ELECTRIC TOASTER OR SIMILAR ARTICLE

Joseph E. Barrett, St. Louis, Mo., assignor to Superior Electric Products Corp., St. Louis, Mo., a corporation of Missouri

Application February 7, 1938, Serial No. 74,950

Term of patent 3½ years

To all whom it may concern:

Be it known that I, Joseph E. Barrett, a citizen of the United States, residing in the city of St. Louis and State of Missouri, have invented a new, original, and ornamental Design for an Electric Toaster or Similar Article, of which the following is a specification, reference being had to the accompanying drawing, forming a part thereof.

In the drawing:

Fig. 1 is a perspective view of an electric toaster,

showing my new design; Fig. 2 is a rear view of the toaster, showing the side opposite that appearing in Fig. 1, and Fig. 3 is an end view, illustrating the end of the toaster opposite that appearing in Fig. 1.

I claim:

The ornamental design for an electric toaster or similar article, substantially as shown.

JOSEPH E. BARRETT.
